DESIGN FOR A CORD RACK OR SIMILAR ARTICLE

Edward J. Nolan, Jr., Detroit, Mich.

Application June 5, 1939, Serial No. 85,351

Term of patent 14 years

To all whom it may concern:

Be it known that I, Edward J. Nolan, Jr., a citizen of the United States of America and a resident of Detroit, in the county of Wayne and State of Michigan, have invented a new, original, and ornamental Design for a Cord Rack or Similar Article, of which the following is a specification, reference being had to the accompanying drawing, forming part thereof.

Figure 1 is a perspective view of a cord rack or similar article, showing my new design.

Figure 2 is a side elevational view of the article illustrated in Figure 1.

I claim:

The ornamental design for a cord rack or similar article, as shown.

EDWARD J. NOLAN, JR.
